Primary Examiner—Celia A. Murphy*(74) Attorney, Agent, or Firm*—Banner & Witcoff, Ltd.(57) **CLAIM**

The ornamental design for a shoe outsole, as shown and described.

DESCRIPTION

FIG. 1 is a bottom front perspective view of a shoe outsole showing my new design;

FIG. 2 is a bottom rear perspective view thereof; and,

FIG. 3 is a bottom view thereof.

The uneven broken lines immediately adjacent to the shaded area represent unclaimed boundaries of the design. The uneven broken line showing of the remainder of the shoe is for illustrative purposes only and forms no part of the claimed design.
